INVENTOR:

Budd J. Jones,

by *Robert Burns*
Attorney.

UNITED STATES PATENT OFFICE.

BUDD J. JONES, OF CHICAGO, ILLINOIS.

ELECTRIC CAR-LIGHTING APPARATUS.

SPECIFICATION forming part of Letters Patent No. 451,732, dated May 5, 1891.

Application filed October 7, 1890. Serial No. 367,353. (No model.)

To all whom it may concern:

Be it known that I, BUDD J. JONES, a citizen of the United States, residing at Chicago, in the county of Cook and State of Illinois, have invented certain new and useful Improvements in Electric Car-Lighting Apparatus; and I do hereby declare the following to be a full, clear, and exact description of the invention, such as will enable others skilled in the art to which it appertains to make and use the same.

This invention relates to that class of lighting apparatus for street-cars in which electricity from any suitable source is employed for lighting or illuminating the main or interior car-lamps, the platform-lamps, and the head-light lamp of electric-motor cars, and the like the objects of the present improvement being, first, to provide a simple and effective arrangement of the electric circuit between the different lamps arranged in series, so that when the head-light is placed in position it will automatically switch out the platform-lamp at such end of the car and take the place of the same in the electric circuit, thus dispensing with the use of the independent switches heretofore used for each platform-lamp; second, to provide an improved socket and electric switch-connections for the head-light, embodying the features of an automatic switch or break for the electric-lamp circuit during the non-use of the lamps, thus dispensing with the independent switch or break for the lamp-circuit heretofore in use in this class of electric car-lighting apparatus.

I attain such objects by the construction and arrangement of parts illustrated in the accompanying drawings, in which—
40 Figure 1 is a sectional elevation of a street-car illustrating the application of my improved lighting apparatus; Fig. 2, a diagram view of the same; and Fig. 3, an enlarged detail section of the head-light socket, with the switch-plug in position to break the electric current to the car-lamps when the same are not required for use.

Similar numerals of reference indicate like parts in the several views.
50 Referring to the drawings, 1 represents the interior car-lamps, arranged in a cluster or otherwise, as found most desirable, and 2 and

3 the platform-lamps, 4 being the positive wire or conductor and 5 the negative wire or conductor, embracing in series the different 55 lamps in the electric circuit.

67 are the head-light socket pieces or blocks arranged at the ends of the car in any suitable position, preferably in front of the dash-board of the car, as shown, and having 6c a cavity or vertical opening to receive the shank 8 of the electric head-light 9. These socket-pieces are formed of any suitable non-conducting material, preferably hard wood, and are provided with spring contact-plates 65 10, 11, and 12, having circuit connections as follows: The vertically-arranged spring-plates 10 and 11 in each of the socket-pieces 6 and 7 are arranged in the main electric circuit formed by the conductors 4 and 5 and the 70 branch or sections 13 of the same that extend from the contact-plates 10 to the platform-lamps 2 and 3. These spring-plates will be in contact when the head-light is not in place, as shown to the left in Fig. 2, and 75 the platform-lamp will consequently be in the electric circuit.

When the head-light is placed in position, its shank 8 will force the contact-plates 10 and 11 apart, breaking the main circuit and 80 establishing a circuit, including the head-light lamp, through the insulated contact-plates 14 and 15 on said shank, that connect electrically with the lamp by conductors, as shown in dotted lines in Fig. 2. At the same time 85 the spring-plate 10 will be forced into contact with the plate 12, that connects with a supplementary wire or conductor 16, which connects with the main circuit at a point past the platform-lamp. By this means when the 90 head-light is inserted in place it will automatically cut out the platform-lamp at the end of the car where said head-light is inserted, and in consequence the resistance on the lamp-circuit will be at all times the same, 95 with no liability of the circuit being at any time broken, with the consequent extinguishment of the lamps, which has been a serious objection to former methods hereinbefore employed.

When the lamp circuit is not required for car-lighting purposes, my improved head-light socket-piece near the positive end of the electric-lamp circuit affords a ready and ef-

fective circuit breaker or switch for said lamp-circuit, a wedge 17 of non-conducting material being pushed between the contact-plates 10 and 11 to separate the same and break the circuit, as clearly illustrated in Fig. 3.

With my improved construction the independent electric switch or break for the lamp-circuit, as well as the duplicate head-light switches heretofore employed, is dispensed with, and the action of the apparatus rendered automatic and easy to manipulate and change, as required.

Having thus fully described my said invention, what I claim as new, and desire to secure by Letters Patent, is—

1. In an apparatus for lighting cars, the combination, with the main lighting-conductors, embracing the car-lamps in series in

the electric circuit, of the supplementary conductor 16, the head-light socket-piece having contact-plates 10, 11, and 12, and the head-light having a plug adapted to enter said socket, substantially as herein described.

2. In an apparatus for lighting cars, the combination, with the main lighting-conductors embracing the car-lamps in series in the electric circuit, of the supplementary conductor 16, the head-light socket-piece having contact-plates 10, 11, and 12, and the non-conducting circuit break-plug 17, substantially as herein set forth.

In testimony whereof I affix my signature in presence of two witnesses.

BUDD J. JONES.

Witnesses:

ROBERT BURNS,
GEO. H. ARTHUR.
